UNITED STATES PATENT OFFICE

165,750

DEHUMIDIFIER

John F. Halbeisen, Detroit, Mich., assignor to
Chrysler Corporation, Highland Park, Mich., a
corporation of Delaware

Application May 14, 1951, Serial No. 15,171

Term of patent 14 years

(Cl. D62—4)

To all whom it may concern:

Be it known that I, John F. Halbeisen, a citizen of the United States, residing in the city of Detroit, county of Wayne, and State of Michigan, have invented a new, original, and ornamental Design for a Dehumidifier, of which the following is a specification, reference being had to the accompanying drawings, forming part thereof, in which:

Fig. 1 is a front elevation of a dehumidifier showing my new design;

Fig. 2 is a rear elevation thereof;

Fig. 3 is a side elevation thereof;

Fig. 4 is a top plan view thereof; and

Figs. 5 and 6 are partial sections taken on the lines 5 and 6 respectively of Fig. 1.

The characteristic features of my design are shown in full lines in the drawings.

I claim:
The ornamental design for a dehumidifier, substantially as shown and described.

JOHN F. HALBEISEN.
